Primary Examiner — Rebecca Tsehay(74) *Attorney, Agent, or Firm* — Howard & Howard
Attorneys PLLC(57) **CLAIM**

The ornamental design for a combined dental floss and brush device, as shown and described.

DESCRIPTION

FIG. 1 is a perspective view of a combined dental floss and brush device;

FIG. 2 is a front view thereof;

FIG. 3 is a back view thereof;

FIG. 4 is a left-side view thereof;

FIG. 5 is a right-side view thereof;

FIG. 6 is a bottom view thereof; and,

FIG. 7 is a top view thereof.

In the drawings, the broken lines represent unclaimed portions of the combined dental floss and brush device and form no part of the claimed design.

1 Claim, 5 Drawing Sheets(56)
